a partnership

Application September 10, 1941, Serial No. 103,268

Term of patent 14 years

To all whom it may concern:

Be it known that I, Charles A. Joslin, a citizen of the United States, residing at North Attleboro, in the county of Bristol and Commonwealth of Massachusetts, have invented a new, original, and ornamental Design for a Hair Brush or Similar Article, of which the following is a specification, reference being had to the accompanying drawing, forming part thereof.

Figure 1 is a rear elevational view of a hair brush or similar article showing my new design;

The bristles are shown only on part of the face in Fig. 2 but it is to be understood that they continue throughout the entire brush face areas.

I claim:

The ornamental design for a hair brush or similar article, substantially as shown and described.

CHARLES A. JOSLIN.
